UNITED STATES PATENT OFFICE

BYRON P. LUCE, OF SAN GERMAN, CUBA

CANE MILL

Application filed September 13, 1928. Serial No. 305,716.

This invention relates to improvements in sugar cane mills, and more especially to sugar cane mills in which the macerating and juice expressing operations are carried out in a more efficient manner than has heretofore been possible.

As is known, the usual cane mill includes one or more pairs of preliminary crushing rolls between which the cane passes in the form of a relatively deep tangled blanket of stalks to be crushed and disintegrated, the crushers being followed by a tandem of three-roll mills in which the disintegrated cane is heavily pressed to extract the juices therefrom, the cane mat being treated to various macerating agents, after each pressing operation in order to dissolve the remaining sucrose.

It has been found in practice that the cane mat upon passing out of a three-roll mill expands rapidly and increases in bulk. It is customary to apply macerating fluids to the cane mat immediately after each pressing operation by the use of sprays, canals, and other devices which depend upon gravity, osmosis, and in the case of pressure nozzles, on force, in order to cause penetration of the fluids into the cane mat. It has been found that the macerating fluids generally do not penetrate much below the surface of the blanket or mat of cane or bagasse, owing to the expansion thereof and the rapid occlusion of air, and where hot liquids or water are used the bagasse becomes puffed up with hot water or steam. It is, in general, an object of the present invention to bring about a better maceration of the blanket or mat of bagasse than has heretofore been possible and to bring the macerating fluid into more intimate contact with all of the bagasse particles.

Another effect of the expansion and increase in bulk of the bagasse mat after passing through a three-roll mill is that the bagasse is presented to the next mill in such condition that the mat does not rapidly pass into the bite of the rolls of this mill, with the effect that the latter is oftentimes choked and the grinding speed of the mill tandem as a whole reduced.

Another object of the invention is to provide means for preventing the choking of any of the mills of the tandem and to bring about a condition in the cane mat previous to its presentation to a three-roll mill such that the mat will readily enter between the rolls of the mill.

Still another object of the invention is to bring about more numerous pressings of the macerated bagasse, and at lighter pressures than heretofore provided in the usual mill.

A still further object of the invention is to provide means for permitting the ready passage of the macerating fluids and juices away from the juice expressing means where these liquids generally collect in pools.

In one of its more specific aspects, the invention relates to an apparatus for effecting the above results in which a travelling surface wedge rests or floats on the blanket of bagasse as it passes from one mill of the tandem to another to flatten out or compress the swollen or expanded bagasse to cause a more thorough penetration of the macerating fluids and to reduce the blanket to a form wherein the next or succeeding mill of the tandem will readily grip the blanket without choking.

To these and other ends, the invention consists in the novel features and combination of parts to be hereinafter described and claimed.

In the drawings,

Fig. 1 is a side elevation of a part of a mill tandem having an extractor, in accordance with my invention, applied thereto;

Fig. 2 is a plan view of the mill tandem shown in Fig. 1, but on an enlarged scale, and partly broken away;

Fig. 3 is a view similar to Fig. 1, but on an enlarged scale, and in section;

Fig. 4 is a view similar to Fig. 3, but showing a modification; and

Fig. 5 is a plan view of the form shown in Fig. 4.

Referring now to the drawings in which I have illustrated my invention by showing a preferred embodiment thereof, the reference numeral 5 indicates in general a mill tandem of which two three-roll mills, gen-

erally designated by reference numerals 6 and 7, are shown, it being understood, however, that the number of these three-roll mills is usually in excess of two and varies from mill to mill. The three-roll mills 6 and 7 may be of any usual or preferred type, and as shown herein comprise the housings 8 and 9, in which are mounted top rolls 10 and 11, cane rolls 12 and 13, and bagasse rolls 14 and 15, the several rolls being mounted in usual or suitable bearings which will not be shown or described in detail.

Between three-roll mill 6 and mill 7 is a conveyor 16, having side walls 17 and 18, extending upwardly from a point adjacent the roll 14 of mill 6 to a point above roll 13 of mill 7, conveyor 16 being provided with a carrier 19 of the endless belt type and made up out of a plurality of overlapping slats 20, supported on a plurality of chains 21, which are received on sprockets 22, 23 and 24. Laterally extending bottom plates 25 and 26 are carried between the side walls 17 and 18 and provide a support for carrier 19 and the cane thereon as the latter passes from mill 6 to mill 7. As is usual, scraper plates 27 and 28 are provided for removing cane adhering to rolls 10 and 14, respectively, scraper plate 28 being provided with a part 29, which extends in the direction of carrier 19, and on which is mounted a plate 30, which is one of the features of this invention, the purpose of which will be pointed out hereinafter.

Adjacent the mill 6 is a trough 31 for macerating liquids, the latter being directed onto the blanket of cane immediately after the latter passes from between rolls 10 and 14 of mill 6.

Except for plate 30, the arrangement described up to this point is substantially that of the usual mill and its operation may be briefly described as follows: A mat of cane either from a preliminary crusher or another three-roll mill, passes between rolls 10 and 12 of mill 6, thence between rolls 10 and 14, where it is heavily pressed and considerable of the juices extracted therefrom. The mat is then discharged from between rolls 10 and 14, over scraper plate 28 and onto belt 19 which conveys the cane to the next three-roll mill, in the particular instance illustrated to mill 7. After being discharged from between rolls 10 and 14, the cane mat is treated to a macerating agent, in the present case, in the form of a liquid which is directed onto the upper surface of the cane mat, as the latter passes from scraper plate 28. According to the present invention, immediately after being subjected to the macerating fluid, the mat of cane passes over plate 30 which serves to turn or fold the mat over to assist in causing the introduction of the macerating fluids into the interior of the mat.

It will be understood that the cane mat

rapidly expands upon being released from the pressure of rolls 10 and 14, and in the usual mill occludes considerable air, resulting in a fluffy mass in which the surface is heavily charged with the macerating fluids, and in which the interior is substantially unaffected thereby. This fluffy mass heavily charged with macerating fluids passes to the next three-roll mill of the tandem roll, and owing to the lightness and expanded condition of the cane, together with the excess of macerating fluids present, the cane does not readily pass into the bite of the rolls but accumulates, and finally if the grinding speed remains unchanged the second mill becomes choked. The failure of the bagasse mat to pass into the bite of the rolls is brought about in part by the excess of macerating fluids present which render the cane particles slippery.

In the present invention, means is provided for bringing about a more thorough maceration of the cane mat than has previously been possible, and in reducing the bulk of the mat prior to its presentation to a succeeding mill, together with the extraction of a certain percentage of the macerating fluids and juices, whereby the mat may readily enter between the rolls of the last named mill.

I prefer to accomplish these results as follows: On either side of conveyor 16, and adjacent the mill 6 are a pair of standards 32 and 33, on which are mounted shaft supporting brackets 34 and 35, having mounted therein rotatable shaft 36. On shaft 36 outwardly from brackets 34 and 35 a pair of arms 37 and 38 are received, shaft 36 being freely rotatable therein and arms 37 and 38 extending towards mill 7 and having on their outer ends brackets 39 and 40 in which is received shaft 41. Mounted on and secured to shaft 36 are a number of sprockets 42, on which are received an equal number of endless chains 43, which pass around floating drum 44, mounted on shaft 41 and extending from side wall 17 of conveyor 16 to side wall 18. Attached to chains 43 are a plurality of overlapping slats 45, the chains and slats therein being driven from shaft 36 by suitable means as, for example, sprocket 46, secured on shaft 36 and driven from sprocket 47 on neck 48 of roll 14 by means of chain 49 which also passes around idler sprocket 50 and 51. It will be noted that the lowest parts of chains 43 and slats 45 move in the same direction and at an acute angle to the upper part of carrier 19, the floating drum 44 being limited in its movement towards carrier 19 by means of brackets 52 and 53, which are adjustably supported on walls 17 and 18 at the bottom of slots 54 and 55, in which the ends of shaft 41 are received. Below the drum 44 and between plates 25 and 26 is a roller 56 supported on suitable bearings on the conveyor walls.

In order that any slack in the chains may be taken up each of the arms 37 and 38 is made up out of two parts 57 and 58, one of which is provided with a righthanded threaded end, while the other has a left-handed threaded end, these ends being joined by connectors 59 which, upon rotation thereof, cause the approach or separation of shafts 36 and 41.

The operation of the improved extractor is as follows: The carrier belt 19 moves from mill 6 towards mill 7, carrying thereon a mat of bagasse discharged from mill 6, which before passing onto the belt is subjected to the action of a macerating fluid introduced from trough 31, and is then turned over by plate 30, as has been previously described, in order to bring about a more thorough dispersion of the macerating fluids through the mat. As the cane mat advances, it is brought into contact with the lower part of the endless belt of the travelling extractor, which moves in the same direction, and preferably substantially at the same speed, or slightly faster than the carrier belt. The lower part of the extractor belt is arranged at an angle to the upper surface of the carrier, so that as the cane mat is carried therebetween it is gradually compressed, the macerating fluids being forced into and through the cane mat and a certain percentage thereof expressed. The amount of pressure brought to bear upon the mat of bagasse depends upon the weight of the extractor, it being possible to increase this pressure, as for example, by adding weights to the shaft 41, or, if desired, compression or tension springs may be used to effect this same purpose. The roller 56 is placed below the floating drum 44 where the greatest pressure is brought to bear on the cane mat in order to support the carrier against this pressure.

The mat of cane after leaving the travelling extractor is thoroughly compressed and evenly saturated with the macerating fluid and readily passes between the rolls of the next mill where a further extraction of the macerating fluids and cane juices is brought about.

In Figures 4 and 5, I have shown a modification in which means is provided for forming one or more grooves in the mat of bagasse through which the extracted juices and macerating fluids may escape during the pressing operations. Herein the scraper plate 60 is provided on its upper surface with a plurality of L-shaped plates 61, one end 62 of each of which is secured to the plate 60, and the other or outer ends 63 of which extend in the direction of and are substantially parallel to the carrier 64. The ends 63 are twisted about 90°, as shown in the drawings. The bagasse mat as it comes in contact with these plates is parted, the twisted ends acting somewhat as a plow and leaving grooves

in the mat which extend through the mat to the carrier. When the mat of bagasse comes into contact with the succeeding juice expressing device, as for example, a three-roll mill, the grooves form passages through 70 which the fluids may readily escape, thus preventing the usual pool of fluids which collects in front of the juice expressing devices.

It will be readily understood that although herein only two three-roll mills are illustrated with an extractor between them, in practice, there will be a plurality of such mills and the improvements of the present application may be introduced between any or all of these mills.

While I have shown a preferred embodiment of my invention, it is to be understood that the same is not to be limited to all the details shown but is capable of modification and variation within the spirit of the invention and the scope of the appended claims.

What I claim is:

1. In a cane mill, means for supporting a blanket of disintegrated cane passing through the mill, means for applying a macerating agent to the cane, means for turning a portion of the blanket of cane over in a direction transverse to the direction of movement of the blanket after maceration thereof, and means for forcing the macerating 90 agent through the blanket of cane after the latter has been turned over.

2. In a cane mill, means for supporting a blanket of disintegrated cane passing through the mill, means for applying a macerating agent to the cane, means for turning the blanket of cane over after maceration thereof, said last named means comprising a plate interposed in the path of the blanket of cane, and means for compressing the blanket of cane after maceration thereof.

3. In a cane mill, a pair of cooperative rolls for pressing a blanket of cane, a scraper plate for removing cane adhering to one of said rolls and supporting the cane discharged 110 from between said rolls, means for applying a macerating agent to the cane after being discharged from between said rolls, means mounted on said scraper plate for turning over the blanket of bagasse after maceration thereof, and means for forcing the macerating agent through the blanket of cane after the latter has been turned over.

4. In a cane mill, a pair of cooperative rolls for pressing a blanket of cane, a scraper plate for removing cane adhering to one of said rolls and supporting the cane discharged from between said rolls, means for applying a macerating agent to the cane after being 125 discharged from between said rolls, means on said scraper plate for turning over the blanket of bagasse after maceration thereof, said last named means comprising a plate mounted on said scraper plate, and means for com- 130

pressing the blanket of cane after maceration thereof.

5. In a cane mill, means for pressing a cane mat to extract the juices therefrom, and means acting on the cane mat prior to its presentation to the pressing means for forming openings extending through the mat in the direction of movement thereof through which the juices may pass when the mat is 10 acted on by the pressing means.

6. In a cane mill, means for pressing a cane mat to extract the juices therefrom, and means acting on the cane mat prior to its presentation to the pressing means for forming grooves in the mat through which the juices may pass when the mat is acted on by the pressing means.

7. In a cane mill, means for pressing a cane mat to extract the juices therefrom, and a 20 plurality of devices extending into the path of the mat of cane as it passes to the pressing means, said devices being adapted to form continuous grooves in the cane mat through which the juices may pass during the pressing operation.

8. In a cane mill, a pair of cane pressing units arranged in tandem, means for conducting cane from one of said units to the other, means for applying a macerating fluid 30 to the cane, means for forming a passage extending through the cane blanket from the upper to the lower surfaces thereof, and means for pressing the mat prior to delivery thereof to the succeeding unit, the fluid passing substantially freely through the passage in the blanket during the pressing thereof.

9. In a cane mill, a pair of spaced units for 40 acting on a blanket of cane to express juice therefrom, a conveyor for conducting the blanket of cane from one unit to the other, means for macerating the cane, means co-acting with said conveyor for forcing the macerating fluid through the cane blanket, and means for forming passages extending through the cane blanket from the upper to the lower surfaces thereof prior to the action of the last named means thereon, the fluid passing through said passages during the action of the forcing means.

50 In witness whereof, I have hereunto set my hand this 4th day of September, 1928.

BYRON P. LUCE.
